BLADE HOLDER

Perry A. McCaskey, Minerva, Ohio

Application May 1, 1942, Serial No. 441,312

8 Claims. (Cl. 30—339)

My invention relates to an implement or device for holding safety razor blades while stropping them.

The advantages and economies attending the practice of sharpening safety razor blades are becoming more appreciated as the practice increases, and this practice recently has been given impetus by the necessity of conserving steel. The advantages of stropping old blades, and frequently new ones, are keenness and smoothness of edge which insure ease, speed and comfort in shaving. Furthermore, the life of a blade is greatly prolonged by stropping, a single blade affording months of satisfactory service.

On the side of economy is not only the conservation of metal effected by the saving of blades, but the construction of my improved holder enables it to be made in part, or entirely, of plastic or other non-metallic material, thus effecting a further saving of metal.

Among the objects of the invention are to provide a razor blade holder that is simple of construction and accordingly inexpensive of manufacture; to provide a device of this class that, notwithstanding its simplicity and cheapness, is strong and durable, and very neat and attractive of appearance, the nature of the construction permitting the use of plastic material or the like in pleasing colors, or color combinations; to provide a razor blade holder that is easily kept clean and sanitary because of the character of its construction and the material from which it may be made; and to provide an efficient razor blade holder that is especially convenient of use in that its construction and mode of operation greatly facilitates the insertion and removal of a blade, and its size, shape, and lightness of weight make the handling of it comfortable and easy and the stropping of the blade a quick and effective operation.

Another object of my invention is to incorporate in a device for holding safety razor blades while stropping them, means for administering a strop treatment or abrasive substance to the strop during the stropping operation, and which will effect a proper application of the treatment or substance to the strop.

The foregoing objects and advantages, with others hereinafter appearing, are attained in the embodiments of the invention illustrated in the accompanying drawing wherein Fig. 1 is a perspective view of one form of the invention, showing it holding a blade in readiness for stropping; Fig. 2 is a perspective view showing the holder held in a hand with the plunger projected for the application of a blade thereto, and indicating the manner of presenting the blade to the

plunger; Fig. 3 is a longitudinal section through the blade holder but showing the plunger in elevation; Fig. 4 is a sectional detail on the line 4—4 of Fig. 3; Figs. 5 and 6 are longitudinal sections through two modifications of the invention, the former showing the plunger projected as for the application or removal of a blade, and the latter with the plunger retracted in the position it occupies when a blade is held by the device in readiness for stropping, and Fig. 7 is a diagrammatic representation of the holder in end elevation with a blade therein, indicating its relation to a strop in a stropping operation, the present view being on a larger scale than the former views.

In all views of the drawing the holder is designated generally by the reference character A, and in Figs. 1, 2 and 7 a safety razor blade of standard size and shape is shown at B. A strop or the like is indicated in dot-and-dash lines in Fig. 7, where it is designated C.

According to the form of the invention illustrated in Figs. 1 to 4, the holder comprises a cylindrical barrel 1, which may be made of any suitable material, desirably plastic. The barrel is provided with substantially diametrically opposed longitudinally extending slits 2 that open through one end of the barrel, the slits, at their open ends, being desirably slightly flared, as indicated at 3. A slot 5 extends longitudinally of the barrel in spaced relation to the transverse plane of the closed ends of the slits 2 and extends to within a short distance of the opposite end of the barrel, said slot being within what may be considered the grip or handle portion of the device. The plane of the slot 5 is preferably perpendicular to that of the slits 2.

Slidable within the barrel 1 is a plunger 10, made of plastic or other suitable material, the same being shown as cylindrical throughout the greater part of its length and of slightly less diameter than the internal diameter of the barrel. The plunger and barrel are shown as of substantially the same length. For a distance inwardly from one end, equal approximately to the length of a safety razor blade, the plunger is made semi-cylindrical. The end portion of the plunger may be given this form in any desired manner, as by cutting or grinding, and, so formed, it has a flat face 11 that is adapted to lie in the plane of the adjacent sides of the slits 2 so that when the plunger is projected, as shown in Fig. 2, and a blade B applied thereto and the plunger retracted, the blade will bear on said flat face 11 and extend out through the slits with its edges in position for stropping in the manner indicated in Fig.

7. For holding the blade in position on the

plunger, the latter is provided with means for engagement within standard openings in the blade, as, for example, lugs or studs 12 that project through the openings *b* of the blade. To hold the inner end of the blade snugly against the flat face 11, the shoulder 13 between the face 11 and the adjacent cylindrical portion of the plunger may be undercut, as indicated in Fig. 3.

Suitably connected to the plunger 10, as by having its inner end secured in a slot of the plunger, is a finger piece 15 that projects out through the slot 5 a short distance beyond the outer surface of the barrel 1, and by engaging the thumb with the finger piece 15 the plunger may be reciprocated within the barrel, as for the purpose of projecting the end of the plunger from the barrel, as shown in Fig. 2, for the application of a blade to the plunger and the subsequent retraction of the plunger to move the blade into the slits 2. The finger piece 15 serves not only as a means for projecting and retracting the blade carrying end of the plunger, but to limit the relative longitudinal movement between the plunger and barrel by its engagement with the ends of the slots 5, and to prevent relative rotation between the said elements.

In the form of the invention illustrated in Fig. 5, the barrel 20 is provided with slits 21, which may be flared at their open ends, as in the previously described form, and operating within the barrel is a plunger 25, formed at one end to provide a flat blade receiving face 26, having studs 27 projecting therefrom, while the opposite end of the plunger is equipped with a head 28 for engagement with the adjacent end of the barrel to limit the distance the blade carrying part of the plunger may be projected beyond the opposite end of the barrel. For the two-fold purpose of preventing the plunger from rotating within the barrel and of limiting the retraction of the plunger, a relatively small pin or the like 29 may be extended through the plunger slightly beyond the inner end of the blade engaging face 26, with one or both of its ends projecting into one or both of the slits 21.

In the form of the invention illustrated in Fig. 6, the barrel 30 may be identical with that of the form shown in Fig. 5, the blade receiving slits of the present barrel being designated 31. A plunger 32 is slidable in the barrel 30 and to prevent accidental dislodgment of the plunger from the barrel the former is made to bear with considerable friction against the inner surface of the barrel by slitting the plunger longitudinally at 33 and spreading the parts on opposite sides of the slit for firm contact with the barrel. The plunger is made slightly longer than the barrel, and its normal condition within the barrel is as shown in the drawing. The end of the plunger adjacent the slitted end of the barrel is formed to provide a flat blade engaging face 35, the same being provided with studs 36.

When it is desired to use the form of the invention at present under consideration, the extending end of the plunger is pushed inwardly to project the blade carrying portion of the plunger beyond the slitted end of the barrel when the plunger may be grasped and withdrawn to the extent necessary to apply a blade to the flat face 35 with the studs 36 projecting through the openings *b* in the blade. After the blade is applied to the plunger, the plunger is rotated, if necessary, to dispose the blade in the plane of the slits 31, and the plunger is pushed in so as to move the blade into said slits. The inward move-

ment of the plunger is stopped by the engagement of the inner end of the blade with the closed ends of the slits 31. As in the former cases, the open ends of the slits may be flared, this being so obvious that specific illustration, in connection with the forms of the invention illustrated in Figs. 5 and 6, is deemed unnecessary.

A feature applicable to all forms of the invention and illustrated in connection with the form shown in Figs. 1 to 4, is the incorporation in the implement of means for applying a strop treating or abrasive substance to a strop. Applied to the barrel 1 within the zone of the blade receiving slits 2 is a strop treatment or abrasive substance, indicated by stippling at *a* in Figs. 1 and 2. This may be accomplished by dipping the barrel into the substance while the latter is soft or in a molten condition, thereafter allowing it to solidify; or the substance may be blasted upon the barrel; or the barrel may be roughened and a deposit of the substance occasionally applied to the roughened portion of the barrel by rubbing it thereover. This substance may occupy either or both sides of the barrel, and as the barrel is drawn across the strop in the manner illustrated in Fig. 7, a very thin deposit of the substance is spread over the strop.

Having thus described my invention, what I claim is:

1. A blade holder comprising a cylindrical tubular barrel having substantially diametrically opposed slits opening through one of its ends, a cylindrical plunger of a length at least not substantially less than that of the barrel slidable in the barrel and provided with blade attaching means accessible for the application of a blade thereto when the portion of the plunger incorporating said means is projected beyond the slotted end of the barrel, the remaining portion of the plunger maintaining connection with the barrel, the blade being adapted to be moved into the slits by the retraction of the plunger, and means constantly restraining the plunger from dislodgment from the barrel.

2. A blade holder comprising a cylindrical tubular barrel having substantially diametrically opposed slits that open through one of its ends, a cylindrical plunger of a length at least not substantially less than that of the barrel slidable in the barrel and provided with blade attaching means accessible for the application of a blade thereto when the plunger is projected a fraction of its length beyond the slotted end of the barrel, the blade being adapted to be moved into the slits by the retraction of the plunger, and parts on the barrel and plunger, respectively, that cooperate to prevent relative rotation between the barrel and plunger and to limit relative longitudinal movement therebetween.

3. A blade holder comprising a barrel having substantially diametrically opposed slits that open through one of its ends, and a plunger slidable in the barrel and provided with blade attaching means accessible for the application of a blade thereto when the plunger is projected beyond the slotted end of the barrel, the blade being adapted to be moved into the slits by the retraction of the plunger, the plunger having a head on its end remote from the blade attaching means for engagement with the adjacent end of the barrel, and means extending laterally from the plunger into one or both of the aforesaid slits.

4. A blade holder comprising a barrel having a slit in its wall that opens through one of its ends, and a plunger slidable in the barrel and

provided with blade attaching means accessible for the application of a blade thereto when the plunger is projected beyond the slotted end of the barrel, the blade being adapted to be moved into the slit by the retraction of the plunger, the plunger being laterally offset intermediate its ends for frictional engagement with the inner surface of the barrel.

5. A blade holder comprising a barrel having substantially diametrically opposed slits that open through one of its ends, and a plunger slideable in the barrel and provided with blade attaching means accessible for the application of a blade thereto when the plunger is projected beyond the slotted end of the barrel, the blade being adapted to be moved into the slits by the retraction of the plunger, the plunger being slit longitudinally intermediate its ends and the portions thereof on opposite sides of the slit being spread apart for frictional engagement with the inner surface of the barrel.

6. A blade holder comprising a barrel of uniform cross section from end to end having a cylindrical bore and provided with substantially diametrically opposed slits that extend longitudinally of and open through one end of the barrel, and a cylindrical plunger of a length at least not substantially less than that of the barrel slideable in the barrel, the end thereof adjacent the slotted end of the barrel being reduced to semi-cylindrical form for a distance substantially equal to the length of said slits thereby to provide a flat face adapted to lie in substantially the plane of said slits and to which a safety razor blade may

be applied, and means extending from said face for engagement within an opening of the blade.

7. A blade holder comprising a barrel having a cylindrical bore and provided with substantially diametrically opposed slits that extend longitudinally of and open through one end of the barrel, and a cylindrical plunger slideable in the barrel, the end thereof adjacent the slotted end of the barrel being semi-cylindrical thereby to provide a flat face adapted to lie in substantially the plane of said slits and to which a safety razor blade may be applied, and means extending from said face for engagement within an opening in the blade, there being a shoulder between the inner end of said face and the adjacent cylindrical portion of the plunger that is undercut to receive the end of a blade applied to the aforesaid face.

8. A blade holder comprising a tubular barrel 20 of substantially uniform cross sectional size and shape from end to end, the same having a slit extending longitudinally thereof from one end a distance approximately the length of a standard safety razor blade, a plunger of cross sectional 25 size and shape to slidably fit within the barrel and of a length at least not substantially less than the length of the barrel, said plunger being provided with a flat blade receiving face adapted to be disposed in the plane of said slit and to be 30 exposed beyond the end of the barrel for the application of a blade thereto by the projection of the plunger beyond the slotted end of the barrel, and means for positioning the blade on said face.
